UNITED STATES PATENT OFFICE.

JOSEPH L. PENNINGTON, OF TONOPAH, NEVADA.

IRRIGATING APPARATUS.

1,258,240.

Specification of Letters Patent.

Patented Mar. 5, 1918.

Application filed April 12, 1917. Serial No. 161,434.

To all whom it may concern:

Be it known that I, JOSEPH L. PENNINGTON, a citizen of the United States, and a resident of Tonopah, in the county of Nye 5 and State of Nevada, have invented a certain new and useful Improvement in Irrigating Apparatus, of which the following is a specification.

My invention relates to improvements in 10 apparatus for irrigating, and it consists in the combinations, constructions, and arrangements herein described and claimed.

An object of my invention is to provide 15 a device which may be used in connection with flowing streams, and by means of which the water from the stream may be elevated above the tanks thereof and delivered to the surrounding country.

A further object of my invention is to 20 provide an irrigating device for elevating water from a stream, which may be operated at a minimum expense.

A further object of my invention is to 25 provide an irrigating device which also serves as a dam to back up the water, thus conserving the same and permitting the use of the water at a time when it is needed.

A further object of my invention is to 30 provide a combined dam and water elevator, which, during flood time, may be raised to permit the flow of water past the device, and which may be lowered when the flood has passed, so as to be in position to elevate 35 the water and to distribute it to the surrounding country.

Other objects and advantages will appear in the following specification, and the novel features of the invention will be particularly pointed out in the appended claims.

40 My invention is illustrated in the accompanying drawings which form a part of this specification, and in which:

Figure 1 is a section through a portion 45 of a river bed showing a battery of the water elevating devices in position;

Fig. 2 is a detail view showing the construction of one of the automatic valves;

Fig. 3 is a detail view showing the outlet valve operating device;

50 Fig. 4 is a similar view showing the intake valve operating device;

Fig. 5 is a section through one of the water elevating devices at right angles to Fig. 1;

55 Fig. 6 is a view similar to Fig. 5, showing the parts in another position;

Fig. 6^a is a section along the line 6^a—6^a of Fig. 1;

Fig. 7 is a perspective view of one of the water receptacles, and

Fig. 8 is a detail view of one of the cams for raising the gate valve.

Referring now particularly to Fig. 1, I have shown therein a section of a stream 1. Disposed in a line at right angles to the direction of flow of the stream is a series 65 of water elevators. In the present instance I have shown this series as being side by side. Each water elevator is constructed like that shown in Fig. 5. In this figure it 70 will be observed that a solid central pile or post 2 is flanked on either side by hollow piles or posts 3, these piles being driven into the bed of the river. Supported on the central post 2 is a frame 4, this frame 75 extending along the battery of series of elevators and also extending upwardly as shown in the drawings. It will be understood that a series of central posts, like that shown at 2, is provided so as to make the 80 framework rigid.

On one side of the framework is a trough 5, this trough being considerably above the level of the bank of the river and extending along the battery of elevators toward 85 the land. As will be seen from Fig. 6^a, the vertical members of the frame pieces 4 have guide slots 6 which are arranged to receive tongues 7 of the casings 8. The individual water elevators of the battery are 90 all alike, and a description of one will suffice for all.

The casing 8 of each elevator consists of a rectangular box, which normally rests at the bottom of the framework 4, being held 95 in this position by weights, the weights in this particular instance being sand boxes 9 secured to the outer side of the casing and having pipes 10 by means of which the sand may be dumped out of the sand boxes so as to 100 cause the casings 8 to float if desired. The sand boxes 9 of the adjacent water elevators are joined together by means of a flexible coupling 11, so that the suction pipe 10 need only be connected with one of the sand 105 boxes to empty them all.

Each casing is provided with an intake valve 12 and an outlet valve 13. These valves are controlled in a manner herein-after described. Within each casing is an 110 interior boxlike structure 14, having a water carrying compartment 15 at its top. The

body portion of the box 14 is filled with air or some light gas, so as to render the box buoyant. Disposed in the water carrying compartment is a float 16 at the end of a lever 5 17, which is connected by means of a rod 18 bent outwardly and then downwardly into a loop 19, see Fig. 4, the latter bearing two pawls 20 and 21 respectively.

The intake valve 12 is operated by means 10 of a star wheel 22, which engages a pin 23, see Fig. 2, on a sleeve 24 which is directly connected with the valve. This sleeve is normally acted on by a spring 25, the arrangement being such that when either of 15 the pawls 20 or 21 engages the star wheel, the latter will be engaged with the pin 23, moving the sleeve 24 against the tension of the spring 25 until the latter has passed the center of its movement, when the spring will 20 suddenly straighten out and throw the valve quickly in the direction in which it is moving. A float 16' on the lever 12' is connected by a rod 18' with a loop 19', which operates the outlet valve 13 through mechanism 25 precisely the same as that already described, and which will operate when the loop 19' is moving in an opposite direction, as will be explained later, due to the fact that the pawls 20' and 21' are oppositely directed from the pawls 20 and 21 respectively.

The receptacle 15 has a valve or outlet gate 26 which is normally held closed by a spring 27, see Fig. 11. The valve has a lever 28 which is arranged to be engaged by an arm 29 on the frame 4, see Figs. 5 and 6.

Each of the receptacles 15 is provided with a pair of inlet gates, such as that shown at 30. These gates are caused to swing upwardly when the buoyant box 14 is in the position shown in Fig. 5, by means of a spring pressed finger 31 carried by the wall of the receptacle 15, and which is arranged to engage the gate. Above the gate opening 40 is a cam 32 which presses the finger 31 inwardly so as to permit the upward movement of the float box 14 and the shutting of the gate 30.

From the foregoing description of the various parts of the device, the operation of 50 this form may be readily understood.

Any number of the water elevators may be arranged in battery near the bank of a river. Consider now Fig. 5. In this 55 figure it will be observed that the box 14 is down as far as it will go, its position being determined by a stop member 33 which extends underneath the box. The gate 30 is open and the water from the stream 1 is flowing past the gate and into the receptacle 15. The floats 16 and 16' rise as the water 60 fills the receptacle. The rods 18 and 18' are moved upwardly as shown in Figs. 3 and 4.

65 When the pawl 21 of the loop 19 reaches

the star wheel 22, it will turn the latter and will give a quick throw to the valve 12 in the manner described, opening the valve and permitting water to enter underneath the buoyant box 14 into the interior of the 70 casing 8. It will be observed that the companion pawl 21' will ride idly over the star wheel 22'.

The water will continue to flow through the inlet valve and the box 14 will continue 75 to rise. As soon as the spring finger 31 passes the cam 32 the gate 30 will be closed and will be held closed by water pressure.

In the upward movement of the buoyant box 14 the lever 28, see Fig. 5, comes into 80 engagement with the stop member 29 which opens the gate valve 26 and permits the water in the receptacle 15 to flow out into the trough 5. In the meantime the box 14 is still rising but when it reaches its upper 85 most position, the pawl 20, see Fig. 4, will throw the star wheel and with it the valve 12 in an opposite direction, closing the intake valve. The water continues to run out of the receptacle 15 and the floats 16 and 16' 90 continue to lower. The lowering of the float 16 lowers the loop 19 but the pawl 20 rides idly over its star wheel 22. The pawl 20', however, engages its star wheel 22' 95 and causes the opening of the valve 13. This lets out the water from underneath the buoyant box 14 and the latter descends. The downward movement of the box causes the downward movement of the loops 19 and 19', and when the pawl 21' engages the 100 star wheel 22 the valve 13 is closed. This is the condition when the buoyant box 14 is in its lowest position, as shown in Fig. 5. As the box 14 descends the stop finger 31 pushes open the gates 30 and the water again 105 enters the receptacle 15. The cycle is then repeated indefinitely.

With a small battery of water elevators one may be rising when the other is falling, but with a large number it is obviously important to have the water deliver to the trough 5 in sequence from the individual elevators.

I claim:

1. In a water elevating device, a casing 115 adapted to be submerged in the bed of a stream, removable weights carried by the casing for holding the latter in its lowered position, a buoyant box slidably disposed within said casing, said box having a water 120 receptacle, a gate carried by the casing for permitting the water of the stream to flow into the receptacle, means for admitting water into the casing to raise the box, means for emptying the receptacle when the box 125 is in its upper position, and a guide frame for guiding the casing in its forward movement when the weights have been removed.

2. A water elevating device comprising a 130 guide frame, a floatable casing slidably dis-

- posed in said guide frame, weights carried by said casing for normally retaining the casing at the bottom of the frame, a slide-
5 able buoyant box disposed within the casing, said box having a water receptacle at its top, a gate carried by the casing for admitting the water of the stream into said receptacle, an inlet at the bottom of the casing for admitting water underneath the buoyant box to float the same, an outlet carried by the casing 65 at the bottom for discharging water from underneath the buoyant box and thereby permitting the return of the box to its lower position, an automatically operated gate valve carried by the receptacle for permitting the discharge of water from the receptacle when the box is in its upper position, and a trough carried by said guide frame for receiving the water discharged from said receptacle. 70
- 10 3. A water elevating device comprising a guide frame, a floatable casing slidably dis-
posed in said guide frame, weights carried by said casing for normally retaining the casing at the bottom of the frame, a slide-
15 able buoyant box disposed within the casing, said box having a water receptacle at its top, a gate carried by the casing for admitting the water of the stream into said receptacle, an inlet at the bottom of the casing for admitting water underneath the buoyant box to float the same, and an outlet carried by the casing at the bottom for discharging water from underneath the buoyant box and thereby permitting the return of the box to its 20 lower position. 75
- 20 4. A water elevating device comprising a guide frame, a floatable casing slidably dis-
posed in said guide frame, weights carried by said casing for normally retaining the casing at the bottom of the frame, a slide-
25 able buoyant box disposed within the casing, said box having a water receptacle at its top, an automatically operated gate carried by the casing for admitting the water of the stream into said receptacle, an automatically con- 80 trolled inlet at the bottom of the casing for admitting water underneath the buoyant box to float the same, an automatically controlled outlet carried by the casing at the bottom for discharging water from underneath the buoyant box and thereby permitting the return of the box to its lower position, an automatically operated gate valve carried by the receptacle for permitting the discharge of water from the receptacle when the box is in its upper position, and a trough carried by said guide frame for receiving the water discharged from said receptacle. 85
- 30 5. A water elevating device comprising a guide frame, a floatable casing slidably dis-
posed in said guide frame, weights carried by said casing for normally retaining the casing at the bottom of the frame, a slide-
35 able buoyant box disposed within the casing, said box having a water receptacle at its top, a gate carried by the casing for admitting the water of the stream into said receptacle, an inlet at the bottom of the casing for admitting water underneath the buoyant box to float the same, and an outlet carried by the casing at the bottom for discharging water from underneath the buoyant box and thereby permitting the return of the box to its lower position, and a gate valve carried by the receptacle for permitting the discharge of water from the receptacle when the box is in its upper position. 90
- 40 6. A water elevating device comprising a guide frame, a floatable casing slidably dis-
posed in said guide frame, weights carried by said casing for normally retaining the casing at the bottom of the frame, a slide-
45 able buoyant box disposed within the casing, said box having a water receptacle at its top, a gate carried by the casing for admitting the water of the stream into said receptacle, an inlet at the bottom of the casing for admitting water underneath the buoyant box to float the same, and an outlet carried by the casing at the bottom for discharging water from underneath the buoyant box and thereby permitting the return of the box to its lower position, and an automatically operated gate valve carried by the receptacle for permitting the discharge of water from the receptacle when the box is in its upper position, and a trough carried by said guide frame for receiving the water discharged from said receptacle. 95
- 50 7. A water elevating device comprising a guide frame, a floatable casing slidably dis-
posed in said guide frame, weights carried by said casing for normally retaining the casing at the bottom of the frame, a slide-
55 able buoyant box disposed within the casing, said box having a water receptacle at its top, a gate carried by the casing for admitting the water of the stream into said receptacle, an inlet at the bottom of the casing for admitting water underneath the buoyant box to float the same, and an outlet carried by the casing at the bottom for discharging water from underneath the buoyant box and thereby permitting the return of the box to its lower position, and an automatically controlled gate valve carried by the receptacle for permitting the discharge of water from the receptacle when the box is in its upper position. 100
- 60 8. A water elevating device comprising a guide frame, a floatable casing slidably dis-
posed in said guide frame, weights carried by said casing for normally retaining the casing at the bottom of the frame, a slide-
65 able buoyant box disposed within the casing, said box having a water receptacle at its top, a gate carried by the casing for admitting the water of the stream into said receptacle, an inlet at the bottom of the casing for admitting water underneath the buoyant box to float the same, and an outlet carried by the casing at the bottom for discharging water from underneath the buoyant box and thereby permitting the return of the box to its lower position, and an automatically controlled gate valve carried by the receptacle for permitting the discharge of water from the receptacle when the box is in its upper position. 105
9. A water elevating device comprising a guide frame, a floatable casing slidably dis-
posed in said guide frame, weights carried by said casing for normally retaining the casing at the bottom of the frame, a slide-
110 able buoyant box disposed within the casing, said box having a water receptacle at its top, a gate carried by the casing for admitting the water of the stream into said receptacle, an inlet at the bottom of the casing for admitting water underneath the buoyant box to float the same, and an outlet carried by the casing at the bottom for discharging water from underneath the buoyant box and thereby permitting the return of the box to its lower position, and an automatically controlled gate valve carried by the receptacle for permitting the discharge of water from the receptacle when the box is in its upper position. 115

JOSEPH L. PENNINGTON.
